UNITED STATES PATENT OFFICE.

JAMES A. HINSON, OF CHICAGO, ILLINOIS; MARGARET HINSON ADMINISTRATRIX OF SAID JAMES A. HINSON, DECEASED.

DRAW-BAR ATTACHMENT FOR RAILWAY-CAR COUPLINGS.

SPECIFICATION forming part of Letters Patent No. 768,854, dated August 30, 1904.

Application filed January 9, 1903. Serial No. 138,439. (No model.)

To all whom it may concern:

Be it known that I, JAMES A. HINSON, of Chicago, in the county of Cook and State of Illinois, have invented certain new and useful 5 Improvements in Draw-Bar Attachments for Railway-Car Couplers; and I do hereby declare that the following is a full, clear, and exact description thereof, reference being had to the accompanying drawings, and to the letters of reference marked thereon, which form a part of this specification.

This invention relates to improvements in draw-bar attachments for car-couplers, and refers more specifically to an improved equalizing attachment designed for equalizing the 15 stresses brought upon the draw-bar and the car-floor frame, to which the attachment is applied, when the car is rounding a curve and also for maintaining the draw-bar in a central 20 position when the car to which it is applied is uncoupled from another car.

The invention consists of the matters hereinafter set forth, and more particularly pointed out in the appended claims.

25 In the drawings, Figure 1 is a fragmentary front elevation of a car with my improved draw-bar attachment applied thereto, showing the draw-bar in transverse section. Fig. 2 is a view, partially in top plan and partially 30 in horizontal section, taken on line 2 2 of Fig. 1. Fig. 3 is a vertical section taken on line 3 3 of Fig. 2. Fig. 4 is a detail view, partially in side elevation and partially in section, of one end of the attachment. Fig. 5 is 35 a transverse section taken on line 5 5 of Fig. 3. Fig. 6 is an end elevation of the attachment. Figs. 7 and 8 are detached views of the 40 stirrups forming part of the attachment constituting my invention.

45 As shown in the drawings, A designates the end sill of the car, and B a carry-iron attached to and depending therefrom and through which the draw-bar C extends, said draw-bar being shown in Figs. 1 and 3 in transverse vertical section.

The improved attachment constituting my invention is made as follows:

D D' designate two closed metal stirrups, made of general rectangular shape in plan

view and alike in all respects, with the exception that the stirrup D' is made somewhat narrower than the stirrup D. Said stirrups D D' consist each of two parallel side members d d and integral end members d' d'. The end members d' extend above the upper margins 55 of the side members and are horizontally and convexly curved on their inner faces. The ends of said stirrups at the junction of the end members d' and the side members are strengthened by parallel ribs d' d', which extend outwardly in alinement with the side members of said stirrups, as more clearly shown in Figs. 6, 7, and 8. The end members d' of said stirrup are made flat. Said stirrups when assembled on the carry-iron B 60 are slipped over the upper arms of said carry-iron before the latter is attached to the end sill of the car, one on each side of said carry-iron. The convexly-rounded end members of the stirrups are located above the horizontal 70 part of the carry-iron B and rest at their lower margins on said horizontal part of the carry-iron, one at each side of the center thereof. The convex faces of said end members d' face each other and are separated sufficiently to 75 afford easy space for the draw-bar. The side members of the stirrups extend diagonally downwardly from said end members d' and cross each other below the horizontal member of the yoke B. The yoke D' is made sufficiently smaller than the yoke D to permit it to pass through said latter stirrup, with one side member of each stirrup located on each side of the horizontal part of the carry-iron B and with the flat end member d' of said 80 stirrups extending transversely beneath said carry-iron.

E designates a bracket which is secured by rivets b or otherwise to the lower member of the carry-iron B. Said bracket is provided 90 with vertical parallel end members e and is open at its lower side. The bracket is shown as made of the same width as the carry-iron B, and the side members of the stirrups D D' are located outside of the bracket, while 95 the flat end members of the stirrups fit flat against the inner faces of the depending end members of the bracket. Said end members

of the bracket and of the stirrups are apertured, and a horizontal bolt F extends through said bracket and the end members of the stirrup to hold the stirrups in place on the bracket.

5 Said bolt is held in place by means of a screw-threaded nut f, which latter is locked on the bolt by a key or cotter-pin f'.

G designates a spiral spring which surrounds the bolt F and is interposed between 10 the end members of the stirrups and acts expansively to hold the outer ends of the stirrups at the outer limits of their movement and the inner ends thereof at the inner limits of their movement. Preferably said bolt is 15 surrounded for a portion of its length by a sleeve F', which fits sufficiently close in the spring to prevent the latter from sagging or becoming twisted on the bolt.

The side members of the stirrups D D' are 20 provided with lugs d⁴ d⁵, respectively, the lugs being formed on the inner faces of the side members of the stirrup D, while the lugs on the stirrup D' are located on the exterior faces of the side members thereof. Said lugs 25 strengthen the stirrups at the angles between the end and side members, and the lugs d⁴ fill the space between the side members of the larger stirrup D and the carry-iron B above the stirrup D and prevent twisting of the up- 30 per part of the outer end member d³ due to the reciprocation of the draw-bar when in contact with the convex end of said stirrup D. Said lugs have obliquely-formed contact- 35 faces, which engage the upper margins of the side members of the stirrups.

The spring G acts to normally hold the end members d⁶ of the stirrups outwardly in contact with the end members e of the bracket E, and thereby to hold the convexly-rounded 40 faces of the end members d² of said stirrups at the inner limits of their movement, and said end members d² when so held are located a distance apart to permit the draw-bar to fit freely therebetween. Said draw-bar is loosely 45 mounted in the draft-rigging in a manner to permit the outer end thereof and the head to swing horizontally when the train is rounding a curve. When said draw-bar swings horizontally, it is swung against the convexly- 50 rounded face of one of the end members d², depending upon the direction of swing of the draw-bar, and said stirrup yields to permit the draw-bar to swing to the necessary extent by reason of its connection with the spring 55 G in the manner stated without bringing objectional stress or strain upon the solid or unyielding parts of the draft-rigging or the floor-frame or platform structure of the car. The movements of the parts due to the swing- 60 ing of the draw-bar in the manner described and the return of the draw-bar to its central position are effected without sudden jars or jerks being brought upon the draft-rigging, the strains and stresses being equalized in all 65 parts of the movement of the draw-bar. More-

over, when the draw-bar is swung to one side of its central position, as when the car to which the device is attached is rounding a curve and a connected car is uncoupled therefrom when in said position, said spring G acts 70 through one of said spring-actuated stirrups, depending upon the direction of inclination of said draw-bar to return the free coupler draw-bar, to its central position, so that the draw-bar head will be in proper position for 75 subsequent coupling with another car when the cars to be coupled are on straight track.

The stirrup D, the side members of which are located outside of the stirrup D', is provided at the ends of its end members d⁶ with notches 80 d⁶, which are adapted to receive the strengthening-ribs d⁷ of the inner stirrup D' when said latter stirrup is shifted outwardly by reason of the swinging of the coupler draw-bar from one side of the central position of the coupler- 85 bar. The said strengthening-ribs d⁷ of the outer end members of said stirrups are separated a sufficient distance apart to pass one on each side of the end members of the carry-iron B when said stirrups are at the outer 90 limits of their movement.

An advantage of the attachment described is that the horizontal swinging movement of the draw-bar of the coupler to the passage of the train about a curve does not bring undue 95 or objectionable torsional stress upon the platform or floor-frame structure of the car such as occurs where the draw-bar is confined between unyielding parts in said platform or floor-frame structure, and at the same time 100 said draw-bar is held from too free a movement, it being confined between the end members d² of said stirrups when occupying its central position. Furthermore, the draw-bar is maintained in its central position when free 105 or not coupled with the companion coupler of an adjacent car, and is therefore in position to register with and to be automatically coupled with such companion coupler.

It is obvious that changes may be made in 110 the structural details shown without departing from the spirit of my invention, and I do not wish to be limited to such details except as hereinafter made the subject of specific claims.

I claim as my invention—

1. In a draft-rigging for car-couplers the combination with a draw-bar and a carry-iron, of a single spring and connections between 115 said spring and the draw-bar acting to transmit the pressure of said springs inwardly in opposite directions against said draw-bar to hold said draw-bar in its central position while permitting the draw-bar to swing in both directions against the action of said 120 spring.

2. In a draft-rigging for car-couplers the combination with a draw-bar and a carry-iron, of two independently-movable members supported on the carry-iron and having parts 125 130

- which extend above said carry-iron, one on each side of the draw-bar and a single spring pressing in opposite directions against said members, and designed to hold the upper ends 5 of said members at the inner limits of their movements and pressed against said draw-bar to hold the latter in its central position, while permitting said members to yield to allow the draw-bar to swing in both directions.
10. 3. In a draft-rigging for car-couplers, the combination with a draw-bar and a carry-iron through which the bar extends, of two independently-movable stirrups having parts which extend above said carry-iron one on 15 each side of the draw-bar and a spring interposed between said stirrups below said carry-iron and designed to hold the upper ends of said yokes at the inner limits of their movement while permitting the stirrups to yield to 20 allow the draw-bar to swing in both directions.
4. In a draft-rigging for car-couplers, the combination with a draw-bar and a carry-iron through which the bar extends, of two independently-movable stirrups slipped over said 25 yoke, one of which is made smaller than and is contained partially within the other stirrup, said stirrups having parts above the carry-iron between which is located the draw-bar and a spring interposed between parts of 30 the stirrups below said carry-iron and constructed to yieldingly hold the parts of the stirrups above the carry-iron at the inner limits of their movement.
5. In a draft-rigging for car-couplers, the combination with a draw-bar and a carry-iron through which the draw-bar extends, of two independently-movable stirrups having parts which extend above said carry-iron one on 35 each side of the draw-bar and cross each other diagonally and extend below the carry-iron, stops on the carry-iron which limit the outward movement of the lower parts of said stirrups, and a spring interposed between the lower parts of said stirrups and normally holding 40 the stirrups against said stops.
6. In a draft-rigging for car-couplers, the combination with a draw-bar, and a carry-iron through which the draw-bar extends, of two independently-movable stirrups having parts 45 which extend above said carry-iron one on each side of the draw-bar and cross each other diagonally and extend below the carry-iron, stops on the carry-iron which limit the outward movement of the lower parts of said stirrups, a bolt extending through the parts of 50 the stirrups below the carry-iron, and a spring surrounding said bolt and holding the stirrups against said stops.
7. In a draft-rigging for car-couplers, the combination with a draw-bar, and a carry-iron through which the draw-bar extends, of two independently-movable stirrups having parts which extend above said carry-iron one on 55
- each side of the draw-bar and cross each other diagonally and extend below the carry-iron, stops on the carry-iron which limit the outward movement of the lower parts of said stirrups, a bolt extending through the parts of the stirrups below the carry-iron, a spring surrounding said bolt and holding the lower 60 parts of the stirrups against said stops, and a sleeve surrounding said bolt within said spring.
8. In a draft-rigging for car-couplers, the combination with a draw-bar and a carry-iron through which the bar extends, of two independently-movable stirrups slipped over said carry-iron, one of which is made smaller than and is contained partially within the other stirrup, said stirrups having parts above the 65 carry-iron between which is located a draw-bar and the side members of the stirrups crossing each other diagonally and extending below the carry-iron, stops on the carry-iron for limiting the movement of the lower ends 70 of the stirrups from each other and a spring interposed between the lower ends of the stirrups and holding the same pressed against the stops.
9. In a draft-rigging for car-couplers, the combination with a draw-bar and a carry-iron through which the bar extends, of two independently-movable stirrups slipped over said carry-iron, one of which is made smaller than and is contained partially within the other 75 stirrup, said stirrups having parts above the carry-iron between which is located a draw-bar and the side members of the stirrups crossing each other diagonally and extending below the carry-iron, stops on the carry-iron for limiting the movement of the lower ends 80 of the stirrups from each other and a spring interposed between the lower ends of the stirrups and holding the same pressed against the stops.
10. In a coupler-centering device, the combination with a stationary support, of a two-part draw-bar centering-guide, the parts of which have vertically-extending lugs engaging the sides of the draw-bar respectively, of a single operating medium connected to and actuating both parts of the guide, substantially as described.
- In testimony that I claim the foregoing as my invention I affix my signature, in presence of two witnesses, this 31st day of December, 1902.
- A. D. 1902.
